UNITED STATES PATENT OFFICE.

JOHN SAMUEL FISHER, OF LONDON, ENGLAND.

TROUSERS.

SPECIFICATION forming part of Letters Patent No. 620,435, dated February 28, 1899.

Application filed March 18, 1898. Serial No. 674,372. (No model.)

To all whom it may concern:

Be it known that I, JOHN SAMUEL FISHER, author, a subject of the Queen of Great Britain, residing at 2 Walpole street, King's road, 5 Chelsea, London, England, have invented certain new and useful Improvements in or Relating to Trousers or Breeches, of which the following is a specification.

This invention relates to trousers or 10 breeches, and has for its object to provide a garment which although in the general form of trousers yet has to a great extent the appearance and comfort of riding breeches or knickerbockers—*i. e.*, knee-breeches for cycling, horse-riding, &c.—and, besides, has a 15 novel and attractive appearance and may be utilized either for men's or women's wear.

In order that my present invention may be 20 easily understood and readily carried into practice, I will proceed to fully describe same with reference to the drawings hereunto annexed.

Figure 1 is a front view of a garment, 25 trousers-breeches, made according to my present invention. Fig. 2 is a side view of same. Fig. 3 represents a man wearing these trousers-breeches for cycling. Fig. 4 represents these trousers-breeches on a man wearing top-boots, thus showing the adaptability of 30 the invention for use with top-boots for riding purposes. Fig. 5 shows these trousers-breeches for ladies' wear, either with or without a skirt, the latter being shown in dotted lines.

35 From the waist *a* down to the knee *b* the garment is made loose or tight fitting, according to taste.

The seams *c* are of the ordinary character 40 as far as just below the knee, where the seam ceases, and according to this invention a flap *d* is formed here and provided with button-holes *d'* therein, while the under part or under flap *e* is provided with suitable buttons *e'*, adapted to be buttoned into said buttonholes *d'*. This flap *d* (or opening at *b*) only extends 45 a short distance downward—such, for instance, as shown in the drawings—and then the seam *c* recommences at *c'* and extends to the bottom *z* of the leg of the garment, each

leg of the garment being correspondingly 50 formed—*i. e.*, as a counterpart of the other.

In Fig. 1 the right leg of the garment is shown with a part—viz., the flap *d*—removed at *x* in order to show the under flap *e*, while in the side view, Fig. 2, the flap *d* is shown 55 laid back or open.

From the knee downward to the bottom *z* of each leg the same may be formed loose or tight fitting, as desired, but advantageously moderately-tight fitting for a space of about five 60 inches, as shown in diagrams, so as to give somewhat the appearance of leggings or gaiters; but in any case that part of each leg of the garment where the flap *d* is provided according to this invention is made to fit closely 65 (when buttoned) around the top of the calf of the leg of the wearer, and this tight-fitting of each leg of the garment just below the knee and extending as far as shown in the drawings prevents the garment from wriggling up 70 or down the legs of the wearer, whether riding a cycle or on horseback, walking, or otherwise. At the same time this tightness being just below the knee leaves the action of the 75 knee-joint perfectly free.

Instead of buttoning the flaps *d* and *e* together, as aforesaid, I may join same by elastic, as in knee-breeches, gloves, &c.

If desired, the lower portion of each leg of the garment may be made to button farther 80 down than the amount shown in the drawings, or, if desired, same may be buttoned all the way down from *b* to *z*, and thus the lower portion of the legs made to fit the wearer tightly (or otherwise) all the way down from 85 below the knee to the bottom *z*.

Having thus described my invention, what I claim as new, and desire to secure by Letters Patent of the United States, is—

1. As a new article of manufacture, trousers adapted to reach from the waist to the feet of the wearer, the inner seam being intact the whole length of the leg, and the outer seam being broken between the knee and the bottom of the trousers-leg, the said trousers-leg having two flaps where the outer seam is discontinued, and means for fastening said flaps together, substantially as described. 95

2. As a new article of manufacture, trousers adapted to reach from the waist to the feet of the wearer, the inner seam being intact the whole length of the leg, and the outer seam being broken between the knee and the bottom of the trousers-leg, the said trousers-leg having two flaps where the outer seam is discontinued, the said flaps being provided

with buttons and buttonholes, respectively, for fastening the two together, substantially as described.

JOHN SAMUEL FISHER.
